CLAIM

The ornamental design for a billiard cue support, as shown and described.

DESCRIPTION

FIG. 1 is a perspective view of a billiard cue support showing my new design;

FIG. 2 is a front elevational view thereof, the rear elevational view being a mirror image thereof;

FIG. 3 is a left side elevational view thereof, the right side elevational view being a mirror image thereof;

FIG. 4 is a top plan view thereof;

FIG. 5 is a bottom plan view thereof; and,

FIG. 6 is a perspective view thereof, shown in its environmental use.

The broken lines showing of a billiard cue is for illustrative purpose only and forms no part of the claimed design.
